UNITED STATES PATENT OFFICE.

DAVID J. SCOTT, OF PLAINFIELD, NEW JERSEY, ASSIGNOR TO ISABELLA SCOTT AND DAVID J. SCOTT, EXECUTORS OF WALTER SCOTT, DECEASED, OF PLAINFIELD, NEW JERSEY.

WEB-PRINTING MACHINE.

1,203,275.

Specification of Letters Patent. Patented Oct. 31, 1916.

Application filed April 10, 1915. Serial No. 20,402.

To all whom it may concern:

Be it known that I, DAVID J. SCOTT, a citizen of the United States, and resident of Plainfield, in the county of Union and State of New Jersey, have invented certain new and useful Improvements in Web-Printing Machines, of which the following is a specification.

The present invention relates to web printing machines whether of the rotary or flat bed type, but is especially advantageous on a rotary lithographic machine, either printing directly from lithographic plates on the impression receiving material, or printing by the offset process, that is, through the medium of a transfer member carrying a rubber blanket.

In all lithographic presses the process of inking up the plates, and, in offset presses also the process of inking up the blanket, requires the operation of the press so that the printing plate shall be dampened and inked in the same way as when the press is in actual operation during printing, so as to bring out the details of the work properly. Since this preliminary inking up operation is apt to last for some time—in some cases as long as 10 or 15 minutes at a stretch—a considerable amount of paper is wasted, because, while no printing is being done, the threaded web continues to be forwarded through the press. This can be avoided by breaking the web when the machine is being run for the purpose of inking up the forms, but this has the disadvantage that it requires the web to be rethreaded before the actual printing can take place. Also it is obvious that the delivery mechanism, or certain parts thereof, bear a timed relation to the printed matter upon the web since folding or cutting must only take place in the margins between the printed matter, and that therefore when threading up the web again care must be taken to restore this proper timed relation between the printing means and the delivery means. In order to rethread the press it is customary therefore to stop the press and such action, in a lithographic press, involves gumming up the plate to prevent the form from oxidation while the press is standing, and again washing off the gum before starting up and printing.

It is the object of the present invention to

provide means whereby the printing machine can be operated with the impression tripped and without moving a web threaded therethrough and through web forwarding or delivery means, and without unthreading the web, so that the waste of paper, due to the incidental operation of working on the plates, may be reduced to a minimum.

Accordingly one feature of the invention consists in a web printing machine comprising web printing means and web forwarding means through which a web is threaded, together with means for driving said printing and forwarding means at correct relative speeds or in timed relation to print and forward the web, and means whereby the printing means may be driven without printing and forwarding the threaded web and without unthreading the web.

The printing means may be of any type suitable for printing a web and the forwarding means may consist of feeding or pulling rollers or of a delivery mechanism, or of both. Suitable driving connections are provided of any type for driving the printing means and the forwarding means or delivery means in timed relation.

The delivery mechanism may be of any approved form and may be adapted to deliver the web in sheet form, either in a folded or unfolded condition.

The means for permitting the operation of the printing members without printing or advancing the threaded web may consist of well-known means for tripping the printing members or may comprise means for separating said members or cylinders of any suitable construction, together with means of any suitable character for stopping the forwarding of the web. Said means for stopping the forwarding of the web may consist of any suitable devices for stopping the moving parts, a simple form of which would be the removal or uncoupling of a gear or belt or other transmission mechanism, but preferably, as shown, a clutch is utilized, which clutch may be of any approved form. This clutch may be interposed at any suitable point in the driving connections between the printing means and the forwarding means and may render idle either the pulling or feeding rolls or the delivery mechanism, or a part thereof, or both.

Any suitable means may be utilized to operate the tripping and web stopping means and such means may be actuated separately by the pressman but in the preferred form, as herein disclosed, a common operating means is provided whereby the impression is tripped and the threaded web is stopped.

Other features of construction, combination of parts and arrangement of elements will appear as the specification proceeds.

In the accompanying drawings the invention is disclosed in several concrete and preferred forms from which, however, changes may be made without departing from the legitimate and intended scope of the invention as expressed in the appended claims.

In the said drawings: Figure 1 is a diagrammatic side elevation of a printing machine having a former folder embodying the invention. Fig. 2 is a diagrammatic side elevation of a printing machine embodying the invention having a flat delivery. Fig. 3 is a diagrammatic side elevation of a machine similar to the one shown in Fig. 1 but disclosing a different means for stopping the advance of the web. Fig. 4 is a diagrammatic side elevation of a machine similar to the ones shown in Figs. 1 and 3 but disclosing a different means for stopping the advance of the sheet. Fig. 5 is a diagrammatic side elevation of a different type of printing machine embodying a modified form of the invention. Fig. 6 is a diagrammatic side elevation showing a printing means different from that disclosed in Fig. 5 and showing a former folder. Fig. 7 is a detail view of one means for stopping the advance of the web. Fig. 8 is a detail view of a breaker knife for severing the web.

Similar characters of reference indicate corresponding parts throughout the several views.

In Figs. 1, 2, 3 and 4 the printing means consist of two printing couples A and B which are adapted to print and perfect a web, each couple consisting in this instance of an impression cylinder 1, a transfer cylinder 2, a plate cylinder 3, together with the usual inking devices 4 and dampening mechanism 5. Adjacent to each impression cylinder is a trip shaft 6 which, by means of well-known connections such as 7, cause the impression cylinder to move in the sliding boxes 8, thereby permitting the impression and blanket cylinders to become separated or to be brought together.

Power is supplied to the machine in any suitable way not shown, and the two printing couples A and B are geared together in a well-known manner, here indicated as a shaft 10, having bevel gears 11 which mesh with corresponding bevel gears 12 with which moves spur gears 13 meshing with similar spur gears on the impression cylinder 1, from which latter motion is transmitted to the other cylinders in a known manner.

Confining now our attention to Fig. 1, C represents a delivery here shown as a former folder of any suitable character, the cylinders and rollers 14 of which are driven from a shaft 15 through the train of spur gears 16 and through bevel gears 17, upright shaft 18, bevel gears 19 and shaft 20, 21 and 22 indicating pulling or feeding rollers, the latter of which is driven from the upright shaft 18 through the train of gears 23 terminating in the intermediate 24. The rotation of the roller 22 is controlled by a clutch D. The shaft 15 is driven from the shaft 10 by means of the train of gears 25.

The clutch D is in the present instance controlled by means of the connection 26, bell crank 27, rod 28, bell crank 29, rod 30 secured to the bell crank 31 on one of the trip shafts 6, the two trip shafts 6 being preferably connected together by means of the lever 32 as shown.

The web E comes from the source of supply 33 and is guided over suitable rollers to the impression cylinder 1 of the couple A, thence by suitable means to the impression cylinder 1 of the couple B, and thence by means of suitable guide rollers to the pulling or feeding rollers 21 and 22, and thence to the delivery C.

When either of the trip shafts 6 is operated the two impression cylinders 1 will be separated from their coacting transfer cylinders and at the same time motion will be transmitted through the connections 30, 29, 28, 27, 26 to the clutch D, which results in the stopping of the rotation of the positively driven roller 22 whereby all movement of the web ceases. If the machine as a whole is now operated with the parts tripped and the web stopped but in threaded position, it is obvious that no printing or feeding of the web will take place but that, nevertheless, the timed relation between the delivery and the printing machine will be maintained. The tension on the paper roll is sufficient to prevent the running cylinders 1 from feeding the web by friction on account of wrap of web around cylinders 1.

In Fig. 7 there is shown a detail view of the parts relating to the clutch D and the roller 22 controlled thereby. In the present instance the intermediate 24 meshes into a sliding gear 34 of double width, said gear being loosely mounted upon the stud 35. Connected to this gear 34 is a clutch 36 adapted to engage with a member 37 fast on the stud 35. The stud 35 carries the positively driven pulling roller 22. When therefore the member 36 is pulled out of engagement with the member 37 the rotation of the roller 22 will cease. The means for actuating this clutch consists in the present

instance of two bell cranks arranged at right angles to each other. One bell crank 38 has one arm connected to the member 36 and has a pivotal movement on the center 39. The 5 other arm 39' of this bell crank is engaged by an arm of the bell crank 40 pivoted at 41. The other arm 42 of this bell crank is suitably connected to the rod 26.

In Fig. 2, a flat delivery F is disclosed 10 provided with pulling rollers 43 and 44. The roller 43 is positively driven by an intermediate 24 in the same manner as described in connection with Figs. 1 and 7, which intermediate 24 receives its motion 15 from the gear 45. The gear 45 is driven by means of shaft 46, bevel gears 47 and shaft 48 which in this case is virtually an extension of the shaft 10. The clutch D is, as before, controlled by the connections 26, 27, 20 28, 29 and 30 leading to the trip shaft 6.

In the form shown in Fig. 3 the elements are substantially the same as those shown in Fig. 1, except that here the clutch D is interposed in the shaft 18 so that when it is 25 disengaged from its companion member the roller 22 will be stopped as will also the roller 14, while the cylinder 140 will continue to operate in timed relation with the printing means. The connections for driving the parts in unison and for controlling the operation of the clutch are the same in this figure as in Fig. 1. In this form therefore only a part of the folder is rendered 30 inactive.

In Fig. 4 the general arrangement is the same as in Figs. 1 and 3 but in this instance the clutch D is interposed in the shafting 15 so that when it is uncoupled from its companion the folder C as a whole will be 40 stopped, as well as the roller 22. When this construction is used the clutch D is so arranged that it can be thrown in only when the elements comprising the delivery bear the proper timed relation to the printing 45 means. This is done by providing the clutch members at proper circumferential positions with respect to each other. The connections for controlling the clutch in this instance comprise the members 28, 29 50 and 30.

In Figs. 5 and 6 the printing couples are of a different character from that shown in the first four figures of the drawing.

In Fig. 5 the printing means consist of 55 two printing couples A' and B', each couple comprising an impression cylinder 49, a lithographic form carrying cylinder 50, together with suitable inking means 51 and dampening mechanism 52. The two impression cylinders 49 are here shown as being geared together and the web E is led first between the impression and plate cylinders of couple A' and then between the impression and plate 60 cylinders of couple B', and thence to the delivery by suitable means.

The means for transmitting motion from the printing means to the delivery is here shown as taking the form of a train of gears 53 which connect from the impression cylinder 49 of the couple A', said train of gears driving the shaft 54. This shaft extends over to the delivery and through suitable connections, as shown, drives the gear 55 on a collecting cylinder. From the gear 55 the intermediate 24 is driven which in turn controls the roller 22. The remainder of the delivery is suitably driven from the gear 55 in a suitable manner not shown. The clutch D here controls the roller 22 in the same manner as described in connection with Figs. 1 and 7 and the clutch is actuated by connections 26, 27, 28, 29 and 30 as before, connecting to the trip shaft 6.

In Fig. 6 the printing mechanism consists of two blanket cylinders 56 which act as printing and impression cylinders with relation to each other, the said blanket cylinders receiving an impression from the plate cylinders 57. Here the web E is led in between the two cylinders 56 and thence to the delivery C. The delivery C is of the same construction as shown and described in connection with Figs. 1 and 7 and the clutch D is controlled by the same connections as previously described. The means for driving the delivery C and the roller 22 consists of the shaft 15 and a suitable train of gears 58 which connect to one of the cylinders 56.

In Figs. 1, 5 and 6 a web severing means 59 is disclosed adjacent to the roller 22. This web severing means is a breaker knife having preferably a serrated edge, as shown in Fig. 8, and is mounted on an arm which is pivotally supported at 60. This breaker knife can be conveniently operated at the same time that the clutch D is operated by providing the extension 61 between the rod 26 and the breaker knife so that when the machine is tripped and the web is stopped the web may be broken or severed at that point.

In Fig. 3 the breaker knife 590 is located adjacent to the cylinder 140 and is actuated by a suitable connection 591 which extends over to the clutch D. In the form shown in Fig. 2 the cutting cylinders 62 will perform the function of breaking the web. It will be observed, however, that this severing of the web does not necessitate a rethreading of it through the machine.

What is claimed, is:

1. A web printing machine comprising: web printing means and web forwarding means through which a web is threaded, means for driving said printing and forwarding means to print and forward the web, and means permitting the driving of the printing means without printing and forwarding and without unthreading the threaded web.

2. A web printing machine comprising: printing means and delivery means through which the web is threaded, means for driving the printing and delivery means thereby printing and delivering the web, and means permitting the driving of the printing means without printing or delivering and without unthreading the threaded web.

3. A web printing machine comprising: printing means and delivery means through which the web is threaded, means for driving the printing and delivery means thereby printing and delivering the web, and means permitting the driving of the printing and delivery means without printing or delivering and without unthreading the threaded web.

4. A web printing machine comprising: printing means, web forwarding means through which the web is threaded, means for driving said printing and forwarding means thereby printing and forwarding the web, means for tripping the printing means, and means for stopping the advance of the threaded web without unthreading the same.

5. A web printing machine comprising: printing means and delivery means through which the web is threaded, means for driving the printing and delivery means thereby printing and delivering the web, means for tripping the printing means, and means for stopping the delivery of the threaded web without unthreading the same.

6. A web printing machine comprising: printing means and delivery means through which the web is threaded, means for driving the printing and delivery means thereby printing and delivering the web, means for tripping the printing means, and means for stopping the delivery of the threaded web without stopping the printing means and without unthreading the web.

7. A web printing machine comprising: printing means, web forwarding means through which the web is threaded, means for driving said printing and forwarding means thereby printing and forwarding the web, means for tripping the printing means, means for stopping the advance of the threaded web without unthreading the same, and a common operating means for the tripping and stopping means.

8. A web printing machine comprising: printing means and delivery means through which the web is threaded, means for driving and printing and delivery means thereby printing and delivering the web, means for tripping the printing means, means for stopping the delivery of the threaded web without unthreading the same, and a common operating means for the tripping and stopping means.

9. A web printing machine comprising: printing means and delivery means through which the web is threaded, means for driv-

ing the printing and delivery means thereby printing and delivering the web, means for tripping the printing means, means for stopping the delivery of the threaded web without stopping the printing means and without unthreading the web, and a common operating means for the tripping and stopping means.

10. A web printing machine comprising: printing means and delivery means through which the web is threaded, means for driving the printing and delivery means thereby printing and delivering the web, and means permitting the driving of the printing means without printing or delivering and without unthreading the threaded web and without disturbing the time relation between the printing means and the delivery means.

11. A web printing machine comprising: web printing means, web forwarding rollers and delivery means through which the web is threaded, means for driving the printing and delivery means and the forwarding rollers, thereby printing, forwarding and delivering the web, means for tripping the printing means, and means for stopping the rotation of the forwarding rollers whereby the web remains threaded, unprinted and stationary.

12. A web printing machine comprising: web printing means and web forwarding means through which a web is threaded, means for driving said printing and forwarding means to print and forward the web, means for permitting the driving of the printing means without printing and forwarding the threaded web, and means for severing the web at a point beyond the forwarding means.

13. A web printing machine comprising: web printing means and web forwarding means through which a web is threaded, means for driving said printing and forwarding means to print and forward the web, means for tripping the printing means, means for stopping the action of the web forwarding means, and means for severing the web at a point beyond the forwarding means.

14. A web printing machine comprising: web printing means and web forwarding means through which a web is threaded, means for driving said printing and forwarding means to print and forward the web, means for tripping the printing means, means for stopping the action of the web forwarding means, means for severing the web at a point beyond the forwarding means, and a common operating device for the tripping, stopping and severing means.

15. A web printing machine comprising: web printing means and web forwarding means, through which a web is threaded, means for driving said printing and for-

warding means to print and forward the web, and means permitting the driving of the printing and forwarding means without printing and forwarding and without unthreading the threaded web.

16. A web printing machine comprising: web printing means and web forwarding means, through which a web is threaded, means for driving said printing and forwarding means to print and forward the threaded web, and means permitting the driving of said printing means while the web remains threaded, unprinted and stationary.

17. A web printing machine comprising: web printing means and web forwarding means, through which a web is threaded, means for driving said printing and forwarding means to print and forward the

threaded web, and means permitting the driving of said printing and forwarding means while the web remains threaded, unprinted and stationary.

18. A web printing machine comprising: web printing means and delivery means, through which a web is threaded, means for driving said printing and delivery means to print and deliver the threaded web, and means permitting the driving of said printing and delivery means while the web remains threaded, unprinted and stationary.

Signed at Plainfield, in the county of Union and State of New Jersey this eighth day of April A. D. 1915.
